Ernest L. Du Pree, Weston, Conn., assignor to Schenley Import Corporation, New York, N. Y., a corporation of New York

Application February 24, 1953, Serial No. 23,744

Term of patent 14 years

(Cl. D58—6)

To all whom it may concern:

Be it known that I, Ernest L. Du Pree, a citizen of the United States of America, residing at Weston, county of Fairfield and State of Connecticut, have invented a new, original, and ornamental Design for a Decanter Bottle, of which the following is a specification, reference being had to the accompanying drawing forming a part thereof.

I claim:

The ornamental design for a decanter bottle, as shown.

ERNEST L. DU PREE.
